RUBBING MACHINE

Harold R. Johnson, Rockford, Ill., assignor to
 H. Johnson Engineering & Sales Co., Rockford,
 Ill., a corporation of Illinois

Application May 26, 1949, Serial No. 95,536

12 Claims. (Cl. 51—66)

1

This invention relates to rubbing machines, and more particularly to those of a non-portable type suited to production rubbing operations on flat strip or panel material and the like.

One of the objects of my invention is to provide a rugged and stationary rubbing machine adapted to use for either wet or dry rubbing operations on flat workpieces which are automatically fed through the machine at an adjusted rate while the rubbing progresses in sequential stages.

As another object, my invention comprehends the provision of a rubbing machine embodying a plurality of rubbing shoes supported for linear reciprocating motion and driven from a single shaft in a manner such that alternate ones of the shoes move in opposed cycles laterally of the direction of movement of work through the machine.

Another object of the invention is to provide a rubbing machine having a plurality of reciprocating rubbing shoes, each of which is individually adjustable in a direction lateral to that of the reciprocating motion.

It is a further object of this invention to provide a rubbing machine embodying rubbing shoes constructed and arranged to establish a firm retaining hold on material providing the rubbing surface of the shoe, while being adapted to ease and rapidity of movement of the rubbing material for renewal purposes.

My invention also has within its purview the provision of a rubbing machine wherein the adjusting and actuating parts are disposed at a level above the level of use of liquid used in wet rubbing operations.

Other objects and advantages of the invention will be apparent from the following description and the accompanying drawings in which similar characters of reference indicate similar parts throughout the several views.

Referring to the three sheets of drawings,

Fig. 1 is a general perspective view taken from one end and to one side of a rubbing machine embodying a preferred form of my invention.

Fig. 2 is a fragmentary and somewhat diagrammatic top sectional view showing portions of the operating structure of the rubbing machine depicted in Fig. 1;

Fig. 3 is a fragmentary end sectional view illustrating operating parts of my preferred rubbing machine, some of which parts are depicted in Fig. 2;

Fig. 4 is a fragmentary vertical side sectional view taken substantially at a position indicated by a line 4—4 in Fig. 3 and in the direction of the arrows;

Fig. 5 is an enlarged fragmentary view of a portion of the structure shown in Fig. 4; and

Fig. 6 is a fragmentary side view of a portion of the structure illustrated in Fig. 5.

2

Considered generally, the exemplary embodiment of my rubbing machine which is depicted for exemplary purposes in the accompanying drawings, and as shown in Fig. 1 thereof, includes a base structure 10 adapted for stationary mounting and includes a top workpiece supporting table 12 at the ends of which are platforms 13 and 14 which facilitate the feeding of workpieces into the machine and the removal of such workpieces therefrom. It is a further function of the platforms 13 and 14 to provide support for large workpieces adjacent the opposite ends of the table 12 as such workpieces are fed through the machine. Framework 15 is secured to the base structure 10 and extends upwardly from the table 12 for supporting operating parts of the machine. In the structure disclosed in Fig. 1, the operating parts include rubbing shoes 16, 17 and 18, feed rollers 19 and 20, a first prime mover 22 which comprises a variable speed motor for driving the rubbing shoes and a second prime mover 23 which is a variable speed motor for driving the feed rollers, including the rollers 19 and 20.

Considered in greater detail, the base structure is preferably enclosed by end panels such as 24 and side panels such as 25, 26 and 27. The framework 15 includes opposed side plates 28 and 29 secured to the base structure on opposite sides of the table 12 and having integral reinforcing ribs 30 extending upwardly along the outer surfaces thereof at positions spaced longitudinally of the table 12. Also at spaced positions along the bottom, the side plates 28 and 29 have opposed openings 32 and 33 therein which are aligned with the opposite ends of the rubbing shoes 16, 17 and 18. At the top, the side plates 28 and 29 are connected and covered by a top plate 34. In addition to the top plate, the tops of the side plates 28 and 29 support and are connected by pairs of channels 35 and 36 which serve as supporting bases for the prime movers 22 and 23 respectively. As further elements of the framework 15, beams 37 and 38 (Figs. 1 and 2) extend between reinforced portions of the side plates 28 and 29 and are secured thereto at their opposite ends at positions above the table 12 to serve as main bearing supports.

The beams 37 and 38 have aligned main bearings 39 and 40 respectively mounted at their mid-portions which main bearings are preferably of the anti-friction type and rotatably support a main drive shaft 42 which extends longitudinally of the machine in parallel relationship to the table. At one end of the shaft, a multiple sprocket 43 is secured thereto, through which sprocket a driving connection is provided to the motor 22 by means such as chains enclosed within a housing 44. At spaced positions along the shaft 42, eccentrics 45, 46 and 47 are drivingly secured to the shaft. The number of such eccentrics cor-

responds to the number of rubbing shoes with which the machine is equipped. Although this number may be varied, it is preferably a plurality greater than two. Also, alternate ones of the eccentrics are varied in their position relative to the shaft in order to dephase the movements of the parts which are driven thereby. In the present instance, the alternate eccentrics are opposed, whereby the parts driven thereby move through cycles in opposed relationship to one another.

At positions aligned laterally of the shaft 42 and table 12 with respect to the eccentrics 45, 46 and 47, rubbing shoe supports 48, 49 and 50 are carried from the side plates 28 and 29, as 15 illustrated in Fig. 3. Since the rubbing shoe supports and rubbing shoes of my disclosed structure are substantially alike, a description of one will suffice for all.

Having particular reference to Figs. 3 and 4, each rubbing shoe support includes a cross beam 52 supported at its opposite ends by shafts 53 and 54, which shafts each have an end secured thereto and extend upwardly therefrom in substantially parallel relationship. On the lower surface of the cross beam 52, ribs 55, 56, 57, 58 and 59 are integrally formed thereon in spaced and substantially parallel relationship; the ribs 55 and 56 being at one end of the cross beam, the ribs 57 and 58 being at the other end of the cross beam and the rib 59 being disposed substantially midway between the formerly mentioned ribs. Each such rib, as shown in Fig. 4, is provided with integral bearing bosses 60 and 62 in spaced relationship and having bearing bores 63 and 64 therein. The bearing bores in the respective bosses are aligned and have substantially parallel cross shafts 65 and 66 supported therein for longitudinal sliding movement. At the mid-portion of the cross beam, an elongated opening 67 is provided; the mid-portion of this opening having the rib 59 extending thereacross.

Bearings 68 and 69 which are secured to the side plates 28 and 29 have bearing bores 70 and 72 therein for slidably receiving the shafts 53 and 54. Upper end portions 73 and 74 of the shafts 53 and 54 are threaded. Also, the bearings 68 and 69 have slots 75 and 76 extending laterally of the bearing bores at the mid-portions of the bearings. These slots have worm gears 77 and 78 mounted therein so as to be supported by and rotatable relative to the respective bearings. The worm gears 77 and 78 are internally threaded to fit the threaded upper portions 73 and 74 of the shafts 53 and 54, whereby those shafts are supported from the bearings 68 and 69 through the worm gears 77 and 78. Initially, the positions of the worm gears 77 and 78 are adjusted so that the cross shafts 65 and 66 are substantially parallel to the table 12. At each such rubbing shoe support, a control shaft 79 is journaled in bearings 80 and 82 in the side plates 28 and 29 and has worm gears 83 and 84 secured thereto and meshing with the gears 77 and 78 respectively. Thus, by manual rotation of a hand wheel 85 secured to a projecting end of the control shaft 79, both ends of the rubbing shoe support are vertically adjusted by a single control.

Rubbing shoes 86, 87 and 88 are supported for reciprocating movement laterally of the table 12 by the rubbing shoe supports 48, 49 and 50. Like the rubbing shoe supports, the rubbing shoes are similar in structure to one another, so that a description of one will suffice for all. Each rub-

bing shoe includes a substantially rigid plate 89 having a plane surface 90 facing the table 12, and opposite which plane surface integrally formed supporting lugs 92 project upwardly at the ends of the rubbing shoe and at positions disposed between the ribs 56, 59 and 57 on the rubbing shoe support. The cross shafts 65 and 66 extend through and are secured to the lugs 92, so that the rubbing shoes and their respective cross shafts are carried for reciprocating movement relative to the rubbing shoe supports.

At the mid-portion of each rubbing shoe, a slide frame 93 extends upwardly and encompasses the main shaft 42. The slide frame has substantially parallel side members 94 and 95 joined at the top by a cross member 96. Parallel tracks 97 and 98 are provided on the inner surfaces of the side members 94 and 95, which tracks are in opposed relationship and carry a slide block 99 for vertical reciprocating movement; the extent of such movement being equal to the full displacement of one of the eccentrics during the rotation of the main shaft. A bearing 100, which is preferably of the anti-friction and self-aligning type, is mounted between the eccentric on the main shaft and the adjacent slide block 99. Thus, since the slide frames are secured to the rubbing shoes, the vertical components of movement produced by rotation of the eccentrics are dissipated in lost or idle motion by producing vertical reciprocating movements of the slide blocks relative to their respective slide frames, while the horizontal components of movement effected by rotation of the eccentrics are transmitted through the slide frames to the rubbing shoes, thereby effecting reciprocating movements of the rubbing shoes laterally of the table 12.

A pad 102 of a relatively soft material such as felt or rubber is used on the plane surfaces 90 of the rubbing shoes for most rubbing operations, such as sanding or polishing. This pad is of uniform thickness and covers the plane surface of the shoe. The pad is covered by a sheet or layer 103 of material which is selected to provide the rubbing surface. For securing the sheet 103 firmly in place during use, and yet providing for the quick and ready replacement of the rubbing sheet when it becomes worn, I have provided side fastening strips 104, as shown in Figs. 4 and 5. These strips are secured to the opposite sides of the plate 89 and extend longitudinally thereof in parallel relationship to the plane surface 90 and preferably at positions set back slightly from that plane surface. Each fastening strip 104 has the longitudinal groove 105 in the lower surface thereof, and each carries a slide strip 106 on its outer side face; the slide strips being supported, as shown in Figs. 5 and 6, by adjustable fastening means such as cap screws 107 which extend through slots 108 disposed obliquely with respect to the lower surfaces of the fastening strips. Each such slide strip has a series of inwardly projecting fingers 109 secured to the lower edge thereof and carrying a clamping rod 110 at a position aligned with the adjacent groove 105 in the fastening strip 104. When the cap screws 107 are loosened, the side strips are movable along and downwardly with respect to the adjacent fastening strips to a position such as that depicted at 106a in Figs. 5 and 6, in which latter position the rod 110 is displaced from the groove 105 to a position such as that shown at 110a. When thus retracted, sand paper or other rubbing material may be moved with relative freedom along the surface of the rubbing shoe until

a new rubbing surface is provided. Then, the clamping strips are raised to the position illustrated in Fig. 5, so that the rods 110 firmly clamp the margins of the sheet rubbing material in the grooves 105. For convenience in supporting a supply of sheet rubbing material, brackets 112 are secured to the side plate 28 and carry a roll 113 of sheet rubbing material on a rod 114 carried by the brackets.

For moving sheet material longitudinally of the table 12 and beneath the rubbing shoes 86, 87 and 88 as well as for holding the sheet material firmly against the surface of the table, a series of rollers 115, 116, 117, 118 and 119 is provided. Preferably two rollers 115 and 116 are mounted at the material input end of the machine to insure a workpiece being held flat against the table as it approaches the first rubbing shoe 86 and passes beneath the surface thereof. The roller 117 is mounted between the rubbing shoes 86 and 87, and the roller 118 is mounted between the rubbing shoes 87 and 88. The roller 119 is at the output end of the machine for effecting removal of a finished sheet from beneath the final rubbing shoe. These rollers are carried and driven by shafts 120, 122, 123, 124 and 125, the axes of which shafts are parallel to one another and substantially parallel to lines of reciprocating movement of the rubbing shoes 86, 87 and 88. Thus, as a workpiece of sheet material is moved longitudinally of the table 12 by the rollers, the movement thereof is in a direction lateral to the reciprocating movements of the rubbing shoes.

As illustrated in Fig. 1, the ends of the roller shafts 120, 122, 123, 124 and 125 are journalled at their opposite ends in bearing blocks 126, 127, 128, 129 and 130, which bearing blocks are supported for limited vertical movement by the reinforcing ribs 30 and the side plates 28 and 29 of the framework. Blocks 132, 133, 134, 135 and 136 are secured to the side plates directly above the bearing blocks 126, 127, 128, 129 and 130 respectively and have self-aligning bearings therein which slidably receive shafts 137, 138, 139, 140 and 142 which are secured to the bearing blocks and extend upwardly through the bearings. Compression springs 143, 144, 145, 146 and 147 on the shafts 137, 138, 139, 140 and 142 and disposed between the stationary blocks and the respective bearing blocks bias the bearings and the ends of the rollers downwardly towards the table 12. With this arrangement of parts, the workpiece is held against the table and gripping force is provided, so that the rollers frictionally engage the upper surface of the workpiece.

For driving the rollers 115, 116, 117, 118 and 119, I have provided a series of sprockets and chains which are driven from the motor 23. As indicated in Fig. 2, a chain 148 extends from a drive sprocket on the shaft of the motor 23 and drivingly engages sprockets 149 and 150 which are drivingly secured to the adjacent ends of the shafts 120 and 123 respectively. A second sprocket 152 on the shaft 120 is drivingly connected to a sprocket 153 on the shaft 122 by a chain 154. A second sprocket 155 on the shaft 123 is drivingly connected to a sprocket 156 on the shaft 124 by a chain 157; and finally a second sprocket 158 on the shaft 124 is drivingly connected to a sprocket 159 on the shaft 125 by a chain 160. Thus, the rollers are positively driven at a uniform speed. Preferably, the motors 22 and 23 are both of a variable speed type

and have manually adjustable elements 162 and 163 thereon for effecting adjustments of the speeds of the rubbing shoes and the movement of the workpiece relative to the rubbing shoes.

5 When the disclosed machine is used for wet rubbing operations, a liquid suited to the purpose of the particular operation is flowed onto the surface of the workpiece, preferably near the rubbing shoes. The liquid flowing from the workpiece is then collected in drain troughs on the edge of the base for disposal. In this connection, it may be readily appreciated that when thus used, the adjusting and operating parts of the machine are above and separated from the path of flow of the liquid.

10 While I have illustrated a preferred embodiment of my invention, many modifications may be made without departing from the spirit of the invention, and I do not wish to be limited to the 15 precise details of construction set forth, but desire to avail myself of all changes within the scope of the appended claims.

15 Having thus described my invention, what I claim as new and desire to secure by Letters 20 Patent of the United States, is:

1. A stationary rubbing machine for work-pieces having flat surfaces and comprising, in combination, a base structure having a top work-piece supporting table, framework secured to the base structure and extending upwardly from the workpiece supporting table, rubbing shoe supports carried by the framework at spaced positions longitudinally of the table and each including cross shafts extending laterally and in parallel relationship to the table, rubbing shoes having faces parallel to the table and including supporting bearings mounted for reciprocating movement on said cross shafts, a drive shaft extending longitudinally of the mid-portion of the table at a position spaced above the rubbing shoes, said framework including bearing supports at opposite ends of said drive shaft, bearings carried by said bearing supports and supporting said drive shaft for rotation, said drive shaft having eccentrics thereon at spaced positions aligned with the rubbing shoes, a slide frame secured to and extending upwardly from each of the rubbing shoes, said slide frames encompassing the drive shaft and having opposed vertical slide tracks therein, bearing means on the eccentrics movable along the slide tracks so that the rubbing shoes reciprocate horizontally relative to the table and the bearing means move vertically relative to the rubbing shoes during rotation of the drive shaft, a prime mover for driving the drive shaft, and means for feeding a workpiece longitudinally of the table.

2. A rubbing machine as defined in claim 1, and wherein said means for feeding a workpiece longitudinally of the table includes rollers at each 60 end of the table adjacent the rubbing shoes as well as between adjacent rubbing shoes, said rollers extending laterally across the table in substantially parallel relationship to one another and being supported from the framework for linear movement from and toward the table, springs 65 for biasing the rollers toward the table, and a second prime mover for driving the rollers.

3. A rubbing machine as defined in claim 1, and wherein said rubbing shoe supports each include similarly threaded shafts extending upwardly at positions near opposite sides of the framework, bearings supporting the threaded shafts for movements axially thereof, worm gears threaded onto the threaded shafts and supported by the latter mentioned bearings for rota-

tion at fixed positions, a lateral shaft supported for rotation by the framework and having worm gears secured thereto and meshing with the first mentioned worm gears, whereby rotation of each lateral shaft effects like movements of opposite ends of one of the shoe supports.

4. A stationary rubbing machine for workpieces having flat surfaces and comprising, in combination, a base structure having a top workpiece supporting table, framework secured to the base structure and extending upwardly from the workpiece supporting table, rubbing shoe supports carried by the framework at spaced positions along the table, rubbing shoes having faces parallel to the table and carried by the said supports for reciprocating movement parallel to and laterally of the table, a drive shaft extending along the mid-portion of the table at a position spaced above the rubbing shoes, said framework including bearing supports at opposite ends of said drive shaft, bearings carried by said bearing supports and supporting said drive shaft for rotation, said drive shaft having eccentrics thereon at spaced positions aligned with the rubbing shoes, a mechanism including a slide frame for connecting each eccentric to one of the rubbing shoes and providing lost motion in one direction so that rubbing shoes are driven horizontally relative to the table and the eccentrics move vertically relative to the rubbing shoes during rotation of the drive shaft, a prime mover for driving the drive shaft, and means for feeding a workpiece along the table in a direction transverse to that of the reciprocations of the rubbing shoes.

5. A rubbing machine as defined in claim 4, and wherein said rubbing shoe supports each embody threaded level adjusting elements at spaced positions, and worm gear drive means manually operable from a readily accessible position for simultaneously effecting control of the positions of the level adjusting elements.

6. A rubbing machine as defined in claim 4, and wherein said means for feeding a workpiece along the table includes a plurality of driven rollers movably supported by the framework in substantially parallel relationship to the table, and springs for biasing the rollers toward the table.

7. A rubbing machine as defined in claim 4, and adapted to the use of sheet material for providing rubbing surfaces on the shoes, and wherein said rubbing shoes each have thereon movable side clamping rails and movable end clamps for retaining the sheet material in place over the face of the rubbing shoe during use.

8. In a rubbing machine, the combination comprising a base structure having a top workpiece supporting table, framework secured to the base structure and extending upwardly from the workpiece supporting table, rubbing shoe supports carried by the framework at spaced positions along the table, said rubbing shoes having faces parallel to the table and carried by the said supports for reciprocating movement parallel to and laterally of the table, a drive shaft extending along the mid-portion of the table at a position spaced above the rubbing shoes, said framework including bearing supports at opposite ends of said drive shaft, bearings carried by said bearing supports and supporting said drive shaft for rotation, said drive shaft having eccentrics thereon at spaced positions aligned with the rubbing shoes, and a mechanism for connecting each eccentric to one of the rubbing shoes so that the rubbing shoes reciprocate horizontally relative to the table as the eccentrics rotate and the eccen-

trics are free to move vertically relative to the rubbing shoes during rotation of the drive shaft.

9. In a rubbing machine adapted to the use of sheet material for providing a rubbing surface, the combination comprising an elongated rubbing shoe having a rubbing plate portion presenting a substantially flat working face, a pad covering the working face, strips secured to and extending along opposite sides of the rubbing plate and having longitudinally grooved surfaces extending along opposite sides of the pad, and clamping means including slide strips movably secured to the outer surfaces of the first mentioned grooved strips and having clamping rods secured thereto in alignment with said grooved surfaces for releasably clamping sheet material in place over the pad.

10. A stationary rubbing machine for workpieces having flat surfaces and comprising, in combination, a base structure having a top workpiece supporting table, framework secured to the base structure and extending upwardly from the workpiece supporting table, rubbing shoe supports carried by the framework at spaced positions longitudinally of the table and each including cross shafts extending laterally and in parallel relationship to the table, rubbing shoes having faces parallel to the table and including supporting bearings mounted for reciprocating movement on said cross shafts, a drive shaft extending longitudinally of the mid-portion of the table at a position spaced above the rubbing shoes, said framework including bearing supports at opposite ends of said drive shaft, bearings carried by said bearing supports and supporting said drive shaft for rotation, said drive shaft having eccentrics thereon at spaced positions aligned with the rubbing shoes, a slide frame secured to and extending upwardly from each of the rubbing shoes, said slide frame encompassing the drive shaft and having opposed vertical slide tracks therein, slides mounted for vertical reciprocating movement on said slide tracks and having bearings therein mounted on the eccentrics so that the slides and rubbing shoes reciprocate horizontally relative to the table and the slides reciprocate vertically relative to the rubbing shoes during rotation of the drive shaft, a prime mover for driving the drive shaft, and means for feeding a workpiece longitudinally of the table.

11. A stationary rubbing machine for workpieces having flat surfaces and comprising, in combination, a base structure having a top workpiece supporting table, framework secured to the base structure and extending upwardly from the workpiece supporting table, rubbing shoe supports carried by the framework at spaced positions along the table, rubbing shoes having faces parallel to the table and carried by the said supports for reciprocating movement parallel to and laterally of the table, a drive shaft extending along the mid-portion of the table at a position spaced above the rubbing shoes, said framework including bearing supports at opposite ends of said drive shaft, bearing carried by said bearing supports and supporting said drive shaft for rotation, said drive shaft having eccentrics thereon at spaced positions aligned with the rubbing shoes, a mechanism including a slide frame and a slide for connecting each eccentric to one of the rubbing shoes and providing lost motion in one direction so that the slides and rubbing shoes reciprocate horizontally relative to the table and the slides reciprocate vertically relative to the

rubbing shoes during rotation of the drive shaft, a prime mover for driving the drive shaft, and means for feeding a workpiece along the table in a direction transverse to that of the reciprocations of the rubbing shoes.

12. In a rubbing machine, the combination comprising a base structure having a top workpiece supporting table, framework secured to the base structure and extending upwardly from the workpiece supporting table, rubbing shoe supports carried by the framework at spaced positions along the table, said rubbing shoes having faces parallel to the table and carried by the said supports for reciprocating movement parallel to and laterally of the table, a drive shaft 15 extending along the mid-portion of the table at a position spaced above the rubbing shoes, said framework including bearing supports at opposite ends of said drive shaft, bearings carried by said bearing supports and supporting said drive shaft for rotation, said drive shaft having eccentrics thereon at spaced positions aligned with the rubbing shoes, and a mechanism including a

10
5

slide frame and a slide for connecting each eccentric to one of the rubbing shoes and providing lost motion in one direction so that the slides and rubbing shoes reciprocate horizontally relative to the table and the slides reciprocate vertically relative to the rubbing shoes during rotation of the drive shaft.
